UNITED STATES PATENT OFFICE.

MICHAEL SNEE, OF LOS ANGELES, CALIFORNIA.

BALL-BEARING RAIL.

Application filed February 27, 1928. Serial No. 257,531.

This invention relates to ball bearing rails, particularly to a type of rail such as is used for railroad tracks.

An object of the invention is the provision of a rail of this character wherein and whereby it is possible to remove the ball bearings with ease without the necessity of taking up the rail from its bed in case any of the said balls should become broken or impaired in function from any cause whatsoever.

This invention constitutes an improvement over my patent for ball bearing rail, United States Patent No. 1,652,461, issued December 13, 1927.

Other objects include simplicity of manufacture, general economy in use and practice, ease in maintenance and great durability and efficiency in actual use and service.

With the above and other objects in view, the invention consists in the novel and useful provision, formation, construction and relative arrangement of parts, members and features all as shown in a certain embodiment in the accompanying drawing, described generally and more particularly pointed out in the claims.

In the drawing:

Fig. 1 is a fragmentary elevation of a rail incorporating the invention;

Fig. 2 is a top plan view of the rail shown in Fig. 1;

Fig. 3 is a cross sectional view on the line 3-3 of Fig. 1, and showing a wheel resting upon said rail, and

Fig. 4 is a perspective view of an element of the invention.

Corresponding parts in all the figures are designated by the same reference characters.

Referring now with particularity to the drawing, the improved device as an entirety is designated by A, the same including a rail a, anti-friction means b, and means c, all of which elements may be used in practicing an embodiment of the invention.

The rail is conventional in form as to parts thereof and includes the usual head 1, web 2 and flange 3. The head of the rail along the side thereof is formed with a longitudinal curved groove 4, and within said curved groove 4 are one or more of the anti-friction means b. In the present instance the said means b constitutes roller bearings. No particular method is outlined as to the forming of the curved groove as it may be formed in numerous manners such as by

boring or casting. Furthermore it will be seen that the roller bearings are adapted to contact with a face 5 of flange 6 of the wheel d, and that the tread 7 of said wheel rests upon the head 1 of the rail. Thus as the wheel revolves upon the rail the roller bearings 5 will contact with the flange 6 and be rotated.

It can be demonstrated that a rail of this character lessens the frictional engagement between the flange of the wheel and the rail and therefore saves wear and tear of the rails and wheel flanges due to jolting motions caused by side sway or unevenness of the track or road bed.

Likewise power necessary to move the rolling stock is reduced. The rails, of course, are made in certain lengths and it is essential to close ends of the grooves 4 where such lengths are joined and this is done by providing a block e for the ends, which is inset within the rail and held to said rail by any convenient means such as shown at 10. Furthermore, a coil

spring 11 is adapted to be within the groove 4 and to bear against the surface of this block and the first roller bearing as shown at 12. It will be noted that the outer surface 13 of said block is substantially in alignment with the periphery of the several roller bearings. This is done in order to overcome shock, to wit, as the wheel rolls upon the track it is essential that the flange thereof should not contact abruptly with any of the roller bearings otherwise they might be cracked or split, and this block permits the flange to be maintained at a proper distance.

This particularly applies when there is any side sway of the rolling stock or where the rails are curved. The coil spring 11 overcomes what is known as backlash, as it is evident that the roller bearings have a tendency to move in the grooves in a direction opposite to movement of the rolling stock, the said springs tending to restore the roller

bearings to a proper position after the rolling stock has moved thereover.

One of the chief features of the present invention resides in the means c. If the rollers should become broken or did not function properly, it would be extremely inconvenient to have to remove a section of the rail to remove broken roller bearings and to overcome such a necessity the means c is introduced. This means constitutes the disc 20 formed with a head 21 and with a screw threaded shank 22. This means c is adapted

to be placed in the rail in such a position that the disc portion 20 is received between two of the rollers as shown at 23 and 24. To this end the rail head would be tapped to receive the screw threaded shank 22 as shown at 25. Of course the head 21 permits the means *c* to be readily secured to the head of the rail. Quite obviously this means will hold the roller bearings 23 and 24 separated and if it becomes necessary to replace any broken bearings, the means *c* may be removed from the rail head and the roller bearings moved along and outwardly through the space that was formerly occupied by said means. The diameter of the disc 20 is of course slightly greater than the diameter of the roller bearings. Quite obviously any number of the means *c* might be provided for any rail length, only one being shown in the present instance. Furthermore the said means *c* may assume various shapes and forms, the principle being to provide some member which may be removed from the rail at selected zones thereof, whereby the roller members may be passed outwardly from the curved groove 4 at the position formerly occupied by the said means before it was removed. While it is true that the end blocks *e* might be removed for a like purpose, yet this would necessitate removing the springs and other parts and would not be quite as satisfactory as the removal of the means *c*.

The shape of the disc 20 might be varied such as by providing a cam face so that the degree of placement of said means within

the rail and the contact of the roller bearings with said means *c* would vary the spacing between the bearings 23 and 24.

It is obvious that various changes, modifications and variations may be made in practising the invention in departure from the particular showing of the drawing without departing from the true spirit thereof.

Having thus disclosed my invention, I claim and desire to secure by Letters Patent:

1. In a rail, rollers within said rail and projecting outwardly from a surface thereof, and means between certain of said rollers for spacing said rollers apart comprising a disc formed with a shank threaded to said rail in the zone of said rollers.

2. In a rail, rollers within said rail and projecting outwardly from a surface thereof, and means between certain of the rollers for spacing said rollers apart comprising a disc formed with a head and with a screw-threaded shank, said screw-threaded shank being threaded to the rail in the zone of said rollers.

3. In a rail, rollers within said rail and projecting outwardly from a surface thereof, and means between certain of said rollers for spacing said rollers apart comprising a disc formed with a shank threaded to said rail in the zone of said rollers, said disc being of greater diameter than the diameter of the rollers.

In testimony whereof, I have signed my name to this specification.

MICHAEL SNEE.
